(57) **CLAIM**

The ornamental design for a tubular container, as shown and described.

DESCRIPTION

FIG. 1 is a perspective view of the tubular container of this invention recognizing that the length of the tubular container can vary.

FIG. 2 is front plan view of the container of FIG. 1, with the back plan view being identical;

FIG. 3 is right side plan view of the container of FIG. 2;

FIG. 4 is a left side plan view of the container of FIG. 2;

FIG. 5 is top plan view of the container of FIG. 2; and,

FIG. 6 is a bottom plan view of the tubular container of FIG. 2, wherein the area within the circular edge of the bottom forms no part of the claimed design.
